SET OF SIGN PANEL LETTERS, NUMERALS AND SYMBOLS

David D. Fishback, 223 S. St. Francis,
Wichita, Kans. 67202

Filed Jan. 5, 1970, Ser. No. 20,763

Term of patent 14 years

Int. Cl. D20—03

U.S. Cl. D96—12

FIG. 1

FIG. 2

FIG. 3

FIG. 4

FIG. 5

FIG. 1 is a face view of a set of sign panel letters showing my new design, the letters A-Q being shown in the view;

FIG. 2 is a similar view of the letters R-Z and numerals 1-7;

FIG. 3 is a similar view of the numerals 8, 9 and 0 of certain symbols;

FIG. 4 is representative of the rear view of any one of the letters, numerals and symbols; and

FIG. 5 is a side edge view thereof.

I claim:

The ornamental design for a set of sign panel letters, numerals and symbols, as shown.
